UNITED STATES PATENT OFFICE.

EDGAR A. RUSSELL, OF WALLINGFORD, CONNECTICUT.

DESIGN FOR A CONDIMENTS-CUP.

SPECIFICATION forming part of Design No. 35,822, dated March 18, 1902.

Application filed November 5, 1901. Serial No. 81,207. Term of patent 7 years.

To all whom it may concern:

Be it known that I, EDGAR A. RUSSELL, a citizen of the United States, residing at Wallingford, in the county of New Haven and State of Connecticut, have invented and produced a new and original Design for Condiment-Cups, of which the following is a specification, reference being had therein to the accompanying drawings, forming part thereof.

This invention relates to a design for a condiment-cup; and it consists in the construction and configuration, as hereinafter described, and shown in the accompanying drawings, in which—

Figure 1 illustrates an elevation and Fig. 2 a plan view thereof.

As shown, the condiment-cup is composed of two parts, the body member 1 and the cover member 2. The body member 1 is cylindrical

in form and provided with a circular bead 3 adjacent to its base, a plurality of smaller beads 4 between the bead 3 and the top, and a curved handle 5. The cover member is substantially dome-shaped, tapering slightly toward the top and terminating in a knob 6 through the neck 7.

Having now described my design, what I claim as new, and desire to secure by Letters Patent, is—

The design for a condiment-cup, substantially as herein shown and described.

In testimony whereof I affix my signature in presence of two witnesses.

EDGAR A. RUSSELL.

Witnesses:

GEORGE E. HALL,
EDWARD J. MAHER.
